UNITED STATES PATENT OFFICE.

THOMAS J. STURTEVANT, OF WELLESLEY, MASSACHUSETTS, ASSIGNOR TO STURTEVANT MILL COMPANY, OF BOSTON, MASSACHUSETTS, A CORPORATION OF MASSACHUSETTS.

ELEVATOR.

1,366,103.

Specification of Letters Patent. Patented Jan. 18, 1921.

Application filed December 18, 1918. Serial No. 267,267.

To all whom it may concern:

Be it known that I, THOMAS J. STURTEVANT, a citizen of the United States, residing at Wellesley, county of Norfolk, and 5 State of Massachusetts, have invented an Improvement in Elevators, of which the following description, in connection with the accompanying drawings, is a specification, like characters on the drawings representing like parts.

The invention to be hereinafter described relates to elevators for elevating fertilizers and other materials.

These elevators usually comprise a casing 15 to contain a conveyer comprising an endless belt having buckets secured thereto at intervals, the belt being guided by upper and lower wheels fast on shafts journaled in bearings mounted in the casing.

20 Certain materials elevated by these elevators, such, for example, as fertilizers, contain ingredients which have a deleterious effect on the inner walls of the casing. Therefore, it is necessary to cover said walls

25 with a protective paint which prevents injury to the walls from such deleterious ingredients, and from time to time it is necessary to repaint the inner walls of the casing, in order that they may always be effectively 30 protected. Heretofore, the painting of the walls has been a difficult operation, because of their inaccessibility. An object of the present invention, therefore, is to provide an elevator casing which is made of sections

35 or units, each provided with a removable wall or door of a length substantially equal to the height of the section or unit to which it is applied, the construction being such that a man may readily enter each of the 40 sections through the doors therefor, and quickly and easily paint the inner walls thereof and perform such other operations therein as may be required.

It is important that the casing should be 45 practically dust tight to protect the operatives from dust which might otherwise escape therefrom and be offensive or injurious to the operatives. Another object of the invention is to provide a door construction for each of the sections which may 50 be tightly secured to the margins of the sections surrounding the opening for the door, so as to prevent escape of dust therefrom.

The upper end of the casing has a hood or portion provided with a discharge opening offset from the body of the casing, and adapted to communicate with a chute for conducting materials to the machine or point desired. As the conveyer belt travels, the 55 buckets pass over the upper wheel and throw their contents out through said opening. These conveyer belts are driven at various speeds, and at higher speeds centrifugal force will throw the buckets outward farther 60 as they commence their downward run than when the conveyer belt is driven at slower speeds. As a consequence, heretofore it has been necessary to provide a substantial clearance between the buckets in their downward 65 run and the inner edge of the discharge opening. As a consequence, it has been found in practice that considerable material 70 will dribble back through this space down into the boot of the casing, and reduce the efficiency of the elevator. Another object 75 of the invention, therefore, is to provide a plate or member projecting from the discharge opening toward the buckets in their downward run to catch the material and 80 guide the same to said opening, thereby greatly reducing, if not eliminating dribble of material from the buckets down into the boot. In order that this plate may closely 85 approach the outer edges of the buckets without being engaged thereby for varying speeds of the conveyer, appropriate means is provided to enable adjustment of the plate with respect to the buckets.

The character of certain materials elevated by the elevator is such that if allowed to stand any considerable period of time, they become hardened, and unless removed, will accumulate in the bottom of the boot and interfere with the travel of the conveyer belt. As a consequence, it is necessary 95 to frequently clean out the material from the bottom of the boot. Heretofore, this has been found to be a difficult, inconvenient operation. Another object of the invention, therefore, is to provide simple and effective 100 means to facilitate cleaning of such material from the bottom of the boot out through the door therefor.

With the aforesaid and other objects of 105 the invention in view, the character of the invention will be best understood by reference to the following description of one good

form of elevator shown in the accompanying drawings, wherein:

Figure 1 is a perspective view of an elevator embodying the invention;

5 Fig. 1^a is a face view of the inner side of the door;

Fig. 1^b is a sectional detail;

Fig. 2 on an enlarged scale is a side elevation of the upper end of the elevator, a 10 portion of the wall thereof being broken away to disclose the plate or member for deflecting materials from the buckets to the discharge opening.

Fig. 3 is a sectional detail looking toward 15 the face of the deflecting plate or member;

Fig. 4 is a detail showing the device for securing the plate or member in different positions of adjustment; and

Fig. 5 is a side elevation of the lower end 20 of the boot of the elevator, a portion of the wall thereof being broken away to disclose the means for facilitating cleaning of material from the bottom of the boot.

Referring to the drawings, the elevator 25 shown therein as one good form of the invention, comprises a casing formed of sheet metal, and comprising a plurality of sections or units 1 varying in number according to the height of the elevator required.

30 Each of these sections, in the present instance, comprises opposed side walls 3 connected by upper plates 5 and lower plates 7 of sufficient width to afford a strong connection for the side plates, and leaving 35 openings nearly equal to the height of the section. To strengthen the plates 5 and 7, they may be provided with angle bars 9 secured thereto adjacent the inner edges thereof.

40 The end openings may be normally closed by doors, each, in the present instance, comprising a plate or panel 11 having side margins 13 adapted to overlap a frame comprising flanges of upright angle bars 15 at opposite sides of the door opening and flanges 45 of the angle bars 9. To strengthen the door panel 11, it may be provided with a pair of angle bar ribs 17 extending longitudinally thereof in spaced relation, and riveted or 50 otherwise secured thereto. These ribs may be connected by a pair of handles 19 to facilitate grasping of the door for the purpose of opening and closing the same. The upper and lower ends of the door may be provided with strips 21 adapted to project beyond the ends of the door and flanges of the angle bars 9 referred to.

The margins of the inner face of the door 55 may be provided with cushion strips 22 (Fig. 1^a) of felt or other suitable material secured in the present instance to the door by shellac and rivets 22^a (Fig. 1^b).

Suitable means may be provided to press the margin strips 22 of the door tightly 60 against flanges of the angle bars 15 and the

angle bars 9, so as to prevent escape of dust between them. To accomplish this, in the present instance, a series of latches 23 may be provided fulcrumed on studs mounted on the angle bars 15 and having portions to 70 engage the door margins 13 and press the strips against the bars 15 and 9. These latches are located at suitable intervals to insure pressure on the entire length of the door.

75 In the present form of the invention, each section is equipped with two such doors, and since they are similar, merely one is shown herein. It will be understood that in some cases one door may be sufficient for each section.

Each section may have angle bars 25 at the upper and lower ends thereof, and angle bars 15 at the sides thereof, and the horizontal flanges of the angle bars of adjacent 85 sections may be connected by suitable bolts, the construction being such that the sections may be readily assembled as desired.

90 Preferably the sections intermediate the upper and lower ends of the casing are of similar construction, and any number may be used according to the height of the elevator required, thereby providing a desirable standardized construction.

95 The upper end of the casing, in the present instance of the invention, comprises a hood including a section 29 provided with a discharge opening 31 offset somewhat from the section directly beneath the same, and serving to deliver materials to a chute 100 (not shown) leading to a machine or point to which materials are to be delivered. Mounted on the section 29 are a pair of sections 33 adjustably connected together by bolts 35 and adjustably connected to the section 29 by bolts 37, the construction being such that the sections 33 may be readily slid away from one another on the section 29 to facilitate access to parts contained therein, more fully hereinafter described.

105 In some instances it is desirable to inspect or have access to the interior of the hood without separation of the sections 33. To accomplish this, one of the sections 33 may be provided with a door 39 connected by 115 hinges 41 with said section, and provided with reinforcing angle bar ribs 43 connected by a handle 45. This door may be normally secured in closed position by suitable latches 47.

120 As stated, heretofore in elevators for the purposes described, considerable loss in efficiency has occurred from the dribble of materials from the buckets through the space between the discharge opening and the downward run of the buckets. Next will be described means for preventing such loss of efficiency. This means, in the present instance, comprises a plate or member 51 extending from the discharge opening 130

31 preferably obliquely toward the downward run of the buckets. Suitable means may be provided to permit adjustment of said plate or member toward or from the 5 buckets according to the speed of the conveyer. This means in the present instance comprises a rod 53 projecting through an eye formed by a reverse bend 55 of the upper end of the plate, and through elongated 10 slots 57 in opposed walls of the section 29, the outer ends of the rod being threaded to receive suitable nuts 58. Large washers 59 at the inner faces of said walls serve to cover the slots, and small washers 60 are 15 interposed between the nuts and the outer faces of said walls. The lower end portion of the plate may rest on an angle bar 61 at the inner side of the discharge opening 31 referred to. A spacing sleeve 62 may be 20 mounted on the rod and confined between the large washers.

The construction is such that the nuts may be loosened to allow adjustment of the 25 rod and plate with respect to the brackets and then the nuts may be tightened to hold the rod and plate in position. The plate may be so adjusted that the buckets will barely escape hitting the same in their downward run, as will be noted in Fig. 2. 30 As a consequence, the plate will catch and direct material to the opening which otherwise would dribble down through the casing into the boot.

As stated, the character of certain materials elevated by these elevators is such that they will harden if allowed to stand any considerable time, and clog the bottom of the boot and interfere with the travel of the 35 buckets on the conveyer. Next will be described means to facilitate cleaning of the material from the boot from time to time and prevent such accumulation of material. This means, in the present instance of the 40 invention, comprises a plate 63 (Fig. 5) of an area substantially equal to the cross section of the bottom of the boot, and located 45 immediately above the same. The ends of the plate 63 may be bent downward to present feet 65 adapted to rest on the bottom 50 of the boot, and a portion 67 of the plate may be curved or inclined upward toward the threshold of the door opening, in the 55 present instance, formed by the plate 7 and the angle bar 9 secured thereto. The construction is such that the operator may 60 readily remove the door from the boot, and then reach in with a suitable tool and scrape the material on the plate 63 outward over the curved or inclined portion 65 of the plate out through the door without interference from the threshold of the door.

The conveyer, in the present instance, 65 comprises a belt in the form of a sprocket chain 69 (Figs. 2 and 5) having buckets

71 secured thereto at intervals, said chain being guided by an upper sprocket wheel 73 fast on a shaft 75 journaled in bearings mounted on the casing section 29 at the juncture of the hood sections 33, the construction being such that convenient access may be had to said shaft, wheel and the portions of the chain thereon on separation of the hood sections as described. The shaft 75 may have a gear 77 fast thereon 70 meshing with a pinion 79 on a shaft 81 journaled in bearings mounted on the casing section 29, said shaft 81 being driven from any suitable source of power.

The sprocket chain is guided at the lower 80 end of the casing by a sprocket wheel 83 (Fig. 5) fast on a shaft 87 journaled in bearings 89 (Fig. 1) mounted on the boot and adjustable to vary the tension of the sprocket chain by a device 91 which may 85 be similar to the adjusting device shown, described and claimed in my copending application, Serial No. 218,647, filed February 23, 1918.

The materials to be elevated may be 90 delivered to the boot through a hopper 93.

It is believed that the operation of the elevator will be readily understood without further elucidation thereof.

Having described one good form of the invention without limiting the same thereto, what I claim as new and desire to secure by Letters Patent is:—

1. In an elevator, the combination of a casing comprising superposed sections, each 100 having opposed sides and opposed ends, a plurality of the sections having openings in ends thereof sufficiently large readily to admit a man into the sections, vertical angle bars at the sides of the openings secured to 105 the sides of the sections, horizontal angle bars at the upper and lower ends of the sections secured to the sides of the sections, independent doors larger than said openings having margins overlapping outer faces of 110 the flanges of the vertical and horizontal angle bars, manually operable securing devices mounted at intervals on the vertical angle bars for pressing the doors in dust-tight relation with respect to the vertical and horizontal angle bars, said devices being adjustable to hold or release the doors, and an endless bucket conveyer mounted in said casing.

2. In an elevator, the combination of an 120 endless bucket conveyer, a casing for said conveyer comprising superposed sections secured together, and sufficiently large to receive both runs of the conveyer, a plurality of said sections having opposed side walls 125 provided with vertical members at edges thereof and horizontal members holding the side walls in spaced relation, said members forming elongated openings sufficiently large readily to admit a man into said sec- 130

tions, doors for said openings having margins overlapping outer surfaces of said vertical and horizontal members, and securing devices distributed along margins of the doors for holding the doors in closed positions, said securing devices being adjustable to allow opening of the doors.

3. An elevator, comprising, in combination, a casing having a hood provided with a discharge opening, shafts journaled in upper and lower bearings, wheels on said shafts, an endless conveyer belt connecting said wheels and having buckets thereon, an inclined normally fixed guide plate extending from said discharge opening toward the down moving buckets and out of the path of the latter, and means adjustably supporting said guide plate, that it may be moved in the direction of the plane of the plate relatively to the downmoving buckets to different fixed positions to cause the inner edge thereof to barely clear the buckets and prevent materials from dribbling down to the bottom of the casing when the conveyer belt is driven at different speeds.

4. An elevator, comprising in combination, a casing having a boot and a hood provided with a discharge opening, a pair of shafts mounted in bearings adjacent the top and bottom of the casing, wheels on said shafts, an endless conveyer belt having buckets thereon and connected to said wheels, said boot having an opening in one side thereof substantially equal to the height of the boot, a door for said opening, means to secure the door tightly to said casing to prevent escape of dust therefrom, a cross member having its upper edge located a substantial distance beneath the lower wheel and forming a threshold at the bottom of the door opening, and a fixed curved or inclined bottom plate extending up to the level of said threshold that materials on said bottom plate may readily be scraped or removed from said plate out through said door opening.

In testimony whereof I have signed my name to this specification.

THOMAS J. STURTEVANT.
